PORTABLE ELECTRIC HEAD LAMP

William F. Koepke, New York, N. Y., assignor of
thirty per cent to Adolph Berg, New York,
N. Y.

Application March 5, 1936, Serial No. 67,217

1 Claim. (Cl. 240—59)

This invention relates generally to electric lamps and more particularly to portable electric head lamps.

An object of the present invention is to provide an electric lamp that can readily be mounted on and carried on the forehead of the user, leaving his hands free.

Another object is to provide a reflector for such a lamp with means for readily adjusting the position of the reflector and lamp bulb so as to direct the glare of the bulb in any desired direction without moving the head and so as to move the reflector and bulb out of the way of obstructions.

15 A further object is to provide such a lamp with means for holding the reflector and lamp bulb in adjusted position.

20 A still further object is to provide such an electric lamp that is simple in construction, inexpensive to manufacture, compact and convenient in use.

25 Other objects and advantages of the improved electric lamp will be apparent from the following description thereof taken in connection with the accompanying drawing in which—

Figure 1 is a front view of the improved lamp and associated parts. Figure 2 is a vertical section of the lamp without the casing. Figure 3 is an end view partly in section. Figure 4 is a 30 plan view of the socket. Figure 5 is a sectional view of the socket on the line 5—5 of Fig. 4. Figure 6 is a section view of a part of the socket on the line 6—6 of Fig. 4.

The improved electric lamp is battery operated and for this purpose I provide a cylindrical metal battery casing 20 in which are encased batteries 21. One end of the casing is closed by a screw threaded cap 22. The opposite end of the casing has a screw threaded metal cap or ring 23. An insulating socket 24 is carried by the cap 23 and has one of its metal contacts 25 extending inwardly of the battery casing and in engagement with a metal post 26 carried at the center of the socket body. The other contact 27 of the socket is electrically connected to the metal cap 23 by means of a plate 28 fixed to the inner side of the cap 23. A spiral spring 29 may be used to keep the parts in engagement. A lug or protuberance 30 may be formed on the face 50 of the socket.

An ordinary electrical plug 31, having the usual prong contacts 32 in engagement with the socket contacts through the socket openings 33, conducts the battery current by means of the conductors 34 to the lamp.

The body of the plug may be grooved to coact with the lug or protuberance 30 on the socket 24 so as to polarize the plug, that is, the plug can only be inserted in such fashion that the outer casing of the battery and the outer casing 37 of 5 the lamp are at the same polarity to prevent accidental short circuiting.

The lamp casing includes a flat base portion 35 and end walls 36, all formed of insulating material. The side walls 37 are formed of sheet 10 metal as well as the top wall 38 which is provided with an opening 39.

Rotatably or tiltably mounted between the end walls 36 is a metal barrel shaped member 40. This barrel member is fixed to metal shafts 41 15 and 42 which are journaled in metal bearings 43 and 44, respectively. A spiral spring 45 on the shaft 41 with one end pressing against the end of the barrel holds the barrel in moved or adjusted position. The barrel is closed at one end by 20 a metal wall 46. The opposite end of the barrel is closed by an insulating disk or wall 47. A metal contact arm 48 is fixed to the inner side of the insulating disk 47 by means of the shaft 41 which extends through the disk. The barrel is fixed to 25 the shaft 41 by the screws 49 and plate 49'.

The conductors 34 extend into the interior of the lamp casing through an opening 50 in one of the end walls 36. One of these conductors is connected to a screw 52 secured in the bushing 43. 30

Secured to the inner top side of the base 35 is a metal conducting strip or plate 53, below the shaft 42.

The top wall of the barrel is provided with an opening and fastened to the edge of this opening 35 is a screw threaded socket member 54 and formed integrally with this socket 54 and concentrically thereof is another smaller socket member 55 having a central opening communicating with the interior of the barrel and being positioned directly above and in alignment with the contact arm 48.

An ordinary miniature incandescent lamp bulb 56 is screwed into the socket 55 with its central terminal extending through the opening in said 45 socket and in engagement with the contact arm 48. The other contact terminal of the lamp bulb is in electrical conductive relationship with the metal barrel through the metal lamp socket 55 and intermediate parts. 50

A switch is interposed between the contact strip or plate 53 and the shaft 42 to close the circuit at this point. This switch comprises a disk body portion 57 formed with a slot in its periphery. A yoke 58 is swingably mounted on the shaft 42 55

with its arms outside of the disk 57. A pin 59 is positioned inwardly and centrally of the yoke with one end positioned in the slot in the disk 57 and its other end in an opening in the cross 5 piece of the yoke. A spiral spring 61 surrounds the pin, with its upper convolution pressed against a shoulder on the pin and its other end seated on the cross piece of the yoke. This spring furnishes a snap action to the movement of the 10 yoke and holds the switch in on or off position. A lever or handle 60 is formed integrally with the disk 57 and extends exteriorly of the casing for the lamp. The yoke is so positioned that its cross piece is adapted to be moved into contact 15 with the contact strip or plate 53. When the lever 60 is moved, the pin 59 is moved by the wall of the slot on the disk. The movement of the pin first compresses the spring 61 and when the pin reaches its dead center position, the spring 20 expands and snaps the yoke into engagement or disengagement with the strip 53. In Fig. 3, the lower portion of the strip 53 is engaging yoke 58. A stop member 62 may be fixed to the top of the base 35 to limit the off swing of the yoke 58. 25 A reflector 63 is removably secured to the larger socket 54 in the barrel and protrudes through the aligned openings in the top walls of the barrel and lamp casing to the exterior of said casing. A lens is supported in the outer end of the reflector. 30

The circuit is completed from the batteries to the lamp bulb through the following instrumentalities: the central terminal of the batteries, socket post 26, socket contact 25, one of the plug 35 prongs 32 and attached conductor 34, screw 52, bushing 43, metal shaft 41, contact arm 48, central terminal of the lamp bulb 56, lamp bulb 56, side terminal of lamp bulb 56, socket 55, barrel 40, wall 46, shaft 42, switch 57, contact plate 53 40 and attached conductor 34, attached plug prong 32, socket contact 27, plate 28, cap 23, battery casing 20 and spring 26 to other terminal.

In using the improved lamp, the lamp casing is placed on the head of the user with the flat 45 base portion 35 placed against his forehead. An elastic band 64 is secured in any suitable manner to the end walls 36 and is placed around the head so as to keep the lamp casing securely in position.

50 The connected battery casing 20 may be placed in the pocket. The circuit is closed by moving the switch handle 60. The hands of the user are then free to carry on other necessary work.

If the user of the lamp is working in close quarters and the protruding reflector is in the way, such reflector may be swung upwardly and downwardly thus reducing the overall width of the device and affording more room. The direction of the glare of the lamp may also be changed without the necessity of moving the head by simply swinging the reflector. The spiral spring 45 pressing against the barrel holds the reflector and bulb in adjusted position. 5

10 A spare lamp 65 may be carried in the inside of the cap 23 for emergency purposes if desired.

I claim:

A portable electric head lamp comprising in combination a cylindrical metal casing, a battery 15 in said casing, a removable metal cap on one end of the battery casing, a socket carried by said cap, a pair of contacts on said socket extending inwardly of the casing, one of said contacts being electrically connected to one terminal of the 20 battery, the other of said contacts being electrically connected with the metal cap, a plug mounted on said socket and having its prongs in electrical connection with the contacts of the 25 socket, a lamp casing having a flat base portion, end and side walls and a top wall having an opening therein, shafts journaled in the end walls of said lamp casing, a metal barrel member fixed to said shafts, a pair of concentrically arranged socket members carried by said barrel, a 30 contact arm carried interiorly of the barrel, a lamp bulb in the inner socket member of the barrel having its central terminal in engagement with the contact arm, the other terminal of said bulb being in engagement with the wall of the 35 socket, a lamp reflector removably mounted in the outer socket of the barrel and extending exteriorly of the lamp casing, a conductor electrically connecting one of said plug prongs with the contact arm in the barrel, a contact plate 40 mounted on the base portion, another conductor electrically connecting the other of said plug prongs with the latter contact plate, and switching mechanism carried by the lamp casing for placing the metal barrel in electrically conductive relationship with the latter contact plate, 45 said switching mechanism including a movable yoke member adapted to be moved into engagement with the contact plate, a handle protruding exteriorly of the lamp casing for actuating said yoke member. 50

WILLIAM F. KOEPKE.
